William D. Steere, Oak Park, Mich., assignor to General
Motors Corporation, Detroit, Mich., a corporation of
Delaware

Application January 18, 1957, Serial No. 44,520

Term of patent 7 years

(Cl. D14—6)

Fig. 1 is a side elevational view of the molding strip;
 Fig. 2 is an enlarged view of the molding strip, the center portion being broken away;

Fig. 3 is a transverse section through the molding strip along the line 3-3 of Fig. 2;

Fig. 4 is a transverse section through the molding strip along the line 4-4 of Fig. 2; and

Fig. 5 is a transverse section through the molding strip along the line 5-5 of Fig. 2.

The automobile shown fragmentarily in broken lines in Fig. 1 is disclosed only for purposes of illustration.

This application is a continuation-in-part of design ap-

plication Serial No. D.33,303, filed November 29, 1954, now abandoned.

I claim:

The ornamental design for a molding strip, substantially as shown and described.
